CARRYING CASE FOR CAMERAS OR THE LIKE

Kendrick T. Parsell, 2121 Orrington Ave., Evanston, Ill.

Filed May 10, 1961, Ser. No. 65,108

Term of patent 14 years

(Cl. D87—5)

Fig. 1

Fig. 3

FIG. 1 is a front perspective view of a carrying case for cameras or the like in closed condition showing my new design;

FIG. 2 is a front perspective view thereof in open condition; and

FIG. 3 is a rear perspective view thereof in closed condition and on a slightly larger scale.

The conventional shoulder strap is shown fragmentarily in all figures for convenience of illustration.

I claim:

The ornamental design for a carrying case for cameras or the like, substantially as shown and described.
